UNITED STATES PATENT OFFICE.

GEORGE A. SIMON, OF BOSTON, MASSACHUSETTS.

CIGARETTE-MACHINE.

1,117,527.

Specification of Letters Patent. Patented Nov. 17, 1914.

Application filed May 1, 1914. Serial No. 835,640.

To all whom it may concern:

Be it known that I, GEORGE A. SIMON, a citizen of the United States, residing at Boston, in the county of Suffolk and State of Massachusetts, have invented new and useful Improvements in Cigarette-Machines, of which the following is a specification.

This invention relates to improvements in cigarette making machines, the object being to provide a simple, inexpensive and durable machine adapted to feed tobacco in a continuous cylindrical form to instrumentalities which roll paper about said cylindrical form, paste said paper in place thereon and cut the finished tube into the desired lengths.

A further object of the invention is to provide an improved means for pasting together the overlapping edges of the paper tube constituting the covering for said cigarette.

The invention consists in the combination and arrangement of parts whereby the above objects and certain other objects hereinafter appearing may be attained, as set forth in the following specification and particularly pointed out in the claims.

Referring to the drawings: Figure 1 is a plan view of a machine embodying my invention. Fig. 2 is a longitudinal sectional elevation of the machine illustrated in Fig. 1. Fig. 3 is a transverse section through the pasting instrumentalities taken on line 3—3 of Fig. 1. Fig. 4 is a detail view of the means for cutting the filled paper tube into the desired length.

Like numerals refer to like parts throughout the several views of the drawings.

In the drawings, 5 represents a base preferably upon which the several instrumentalities comprising the machine are mounted. A tobacco receptacle 6, preferably funnel shaped, is mounted upon supports 7 above the base 5, said receptacle terminating in a depending cylindrical discharge tube 8 at the smaller end thereof. A chute 9, preferably cylindrical in shape, is secured to the discharge end of the tube 8, said chute being of substantially larger diameter than said discharge tube and bent to form an elbow adapted to conduct tobacco from a vertical to substantially a horizontal direction. The forward end of said chute projects into a former 10 which is constructed to receive a continuous strip of paper and curl said paper into a cylindrical tube.

Means are provided for feeding a continuous cylindrical rod of tobacco from the receptacle 6 to the paper tube which is being formed by the former 10, said means preferably consisting of a rotatable helical member 11 arranged longitudinally of the discharge tube 8, the upper end of said member being journaled to rotate in a bearing 12 formed in a support 13 at the upper end 65 of the receptacle 6. A bevel gear 14 is secured to the upper end of the member 11 which gear is adapted to mesh with a bevel gear 15 fast to a driving shaft 16, said shaft being preferably operated by hand by means 70 of a crank 17.

The helical member 11, which, in other words, is a screw, is adapted to feed the tobacco represented at 18 through the discharge tube 8 and the chute 9 to the former 10 in a cylindrical form as indicated at 18', said chute 9, as hereinbefore stated, being slightly larger in diameter than the tube 8, thereby permitting the rod of tobacco to pass therethrough with little or no resistance. As said tobacco is laid in said former, a strip of paper 19 is simultaneously fed into said former from a roll 20 mounted upon a shaft 21, by means of a pair of feed rolls 22 positioned adjacent to said former, 85 said rolls having their peripheries grooved to conform to the shape of the completed tube of paper. The rolls 22 are secured to shafts 23 arranged substantially parallel to each other and extending transversely of the 90 tube, said shafts also having spur gears 24 fast thereto which mesh one with the other and cause said rolls to be simultaneously rotated. One of the shafts 23, preferably the upper one, is rotated through a pair of 95 bevel gears 25 and these gears are in turn operated by a shaft 26 extending longitudinally of the machine and in turn operatively connected through gears 27, shaft 28 and gears 29 to the driving shaft 16. 100

The paper former 10 is so constructed that it will receive the paper 19 at the end 30 substantially flat in cross-section and roll said paper into a cylindrical form, as shown at 19' in Fig. 3 with the edges of the paper 105 overlapping each other preferably at the top. As the tube of paper together with the rod of tobacco 18' leaves the former 10, means have preferably been provided for pasting the overlapping edges of said tube 110 together, said means preferably consisting of a disk 31 secured to a shaft 32 rotatably

mounted in suitable supports 33, said shaft being preferably rotated by a pulley 34 fast thereto and connected by a belt 35 to a pulley 36 fast to a shaft 37, said shaft 37 being 5 operatively connected to the shaft 26 preferably by a belt 38 engaging pulleys 39 and 40 on said shafts 37 and 26 respectively.

The disk 31 is arranged to project through an opening or slot 41 in the bottom of a 10 paste receptacle 42 and between the overlapping edges of said tube 19' and collects a small amount of paste from said paste receptacle, which, during its contact with the overlapping edges of the tube 19', it applies 15 thereto. The tube 19' at this time is supported in a trough 43 within which is mounted a roller 44 and as said tube is fed longitudinally of said trough, said roller is adapted to engage the uppermost of said 20 overlapping edges to press said edges together and thus cause the same to adhere one to the other.

A second set of rolls 45, similar to the rolls 22, is provided at a substantial distance 25 from said rollers 22 and adapted to engage the tube 19' at the sides rather than at the top and bottom as do the rolls 22; thus it will be seen that said tube is entirely surrounded by rolls. The rolls 45 are preferably 30 operatively connected together by spur gears 46 to which a rotary motion is imparted by the shaft 37, hereinbefore referred to, and on which one of said rolls is preferably mounted. The trough 43 continues 35 to guide the tobacco filled tube of paper for a distance beyond said rolls 45 to a cutter 47 secured to a shaft 48, said shaft being operatively connected by a belt 49 and pulleys 50 and 51 to the shaft 26, said 40 pulleys being of suitable proportions to operate said cutter to cut the tube 19' into the desired lengths as it is advanced to the cutter 47.

The general operation of the machine 45 hereinbefore specifically described is as follows: The tobacco is placed in the receptacle 6 and a roll of paper 20 mounted upon the shaft 21 and the end thereof lead into the former 10 wherein it is shaped to form a 50 cylinder and started between the rolls 22. The driving shaft 16 is then rotated and the several instrumentalities hereinbefore described set into operation to respectively feed the tobacco 18 in the form of a rod to the former 10 where the paper is coiled thereabout and pasted by the disk 31, rolled down by the roller 44 and rolls 22 and assisted by the rollers 45 which move said tube along the trough 43 to the cutting instrumentalities 55 where predetermined lengths of said tube are cut off.

From the foregoing description it will be seen that simple and efficient means are

provided for accomplishing the objects of the invention, but while the elements herein 65 shown and described are well adapted to perform the functions set forth, it is obvious that various minor changes may be made in the proportions, shape and arrangement of the several parts, without departing from 70 the spirit and scope of the invention as defined in the appended claims.

Having thus described my invention what I claim and desire by Letters Patent to secure is:

75 1. In a cigarette machine instrumentalities for forming a cylindrical tube of sheet material with the edges of said sheet material overlapping, an adhesive receptacle provided with a slot adjacent the bottom thereof, a disk adapted to protrude through said slot into contact with the adhesive in said receptacle, said disk also adapted to project between the overlapping edges of said cylindrical tube, and means to rotate said disk to 80 transfer a portion of the adhesive in said receptacle to the overlapping edges of said tube.

85 2. A cigarette machine having, in combination, a receptacle adapted to contain tobacco, a cylindrical discharge tube for said receptacle, a screw arranged longitudinally of said discharge tube, adapted to feed tobacco from said receptacle through said discharge tube, means to feed a continuous 90 strip of paper transversely of said discharge tube, a curved cylindrical chute attached to said discharge tube and substantially larger in diameter than said tube adapted to conduct tobacco from said discharge tube to 100 said strip of paper, means to roll said strip of paper about said tobacco, means to paste the edges of said paper together, and means adapted to cut off a portion of the tobacco filled paper.

105 3. In a cigarette making machine a receptacle adapted to contain tobacco, a depending discharge tube therefor, means to feed a continuous strip of paper transversely of said discharge tube, a curved 110 cylindrical chute substantially larger in diameter than said discharge tube and attached to the discharge end of said tube adapted to direct the tobacco discharged from said tube in a direction substantially 115 parallel with the line of movement of said paper, and means adapted to form said paper into a cylinder with said tobacco therein.

120 In testimony whereof I have hereunto set my hand in presence of two subscribing witnesses.

GEORGE A. SIMON.
